BUTTER AND LIKE DIVIDER

Johannes Benz, Dusseldorf, Germany

Application November 4, 1931, Serial No. 572,961,
and in Germany November 6, 1939

5 Claims.

(Cl. 31—1)

The object of the present invention is to obtain a method whereby butter, margarine, and other plastic substances may be divided into portions of uniform shape and exact weight, and the invention consists essentially in forming the material into a continuous stream of uniform cross-section, cutting off uniform portions from said stream, pressing said portions into uniform shape, and rejecting in such pressing all material in excess of a given quantity.

A device for carrying out this method comprises a plurality of open-ended moulds of a cross-section substantially equal to that of the stream, the latter being inserted into the moulds against an adjustable plunger and severed so as to leave a uniform portion thereof in each mould whereupon said portion is compressed in the mould between opposing press plungers, means being provided for discharging from the mould all material not containable between the plungers, and means being provided for expelling the pressed and corrected portions from the mould.

The moulds may be attached to a rotatable carrier which is intermittently rotated for moving the moulds from one operating position to another.

Fig. 1 of the accompanying drawing represents a front view of a rotatable mould carrier, and

Fig. 2 is a side view, partly in section, of the carrier of the different plungers.

In the illustrated arrangement four open-ended moulds *b*, *c*, *d*, *e* are carried at the ends of radial arms connected by means of a boss to a rotatable shaft *a* which is subjected to intermittent motion for passing the moulds successively through different operating stations 1, 2, 3 and 4. The material to be divided is formed into a continuous stream *f* which moves over rollers *g* in the direction of the arrow 5 in the first operating station. The moulds, which are of a cross-section substantially equal to that of the stream *f*, are held so as to receive the end of the stream, and a plunger *i* connected to a guide rod *k* is introduced into the mould from the opposite end thereof so as to form an abutment for the stream. The extent to which the plunger enters the mould is adjustable and regulated so that the portion of the stream admitted into the mould is preferably slightly in excess of a given weight. A cutter *h* is operated so as to sever the stream close to the mould.

In the second operating station there are two opposing press plungers *l* and *n* connected respectively to guide rods *m* and *o*. These press plungers enter the mould and press the material into a given shape. The space between the advanced

plungers is regulated so as to contain exactly the desired weight to be given to each portion of the material. To allow superfluous material to escape from the mould, the plunger *n* is formed with apertures *p* which open into a hood *q* whence the discharge materials drop into a receiver *r* for further utilization. By allowing in this manner for the supply and discharge of excess in material, an exact proportioning of material in the pressed portions can always be ensured.

In the third station a plunger *s* is provided which is guided by a rod *t* and which enters the mould for expelling the pressed portion *u* from the latter. A table *v* may be arranged to receive it. The fourth station can either be idle or provided with means for cleaning or moistening the empty moulds.

The plunger *n* may be embossed for making ornamental impressions on the butter portions.

The discharged butter portion *u* may be pushed, together with a wrapping paper, through a device which wraps the paper round it in known manner.

Naturally arrangements may be made for moving the different operating plungers past one or a plurality of stationary moulds, and instead of retaining the material in the same mould during the different operations, each portion may be passed through a plurality of moulds.

The different plungers and other elements are controlled and operated by known means.

I claim:

1. A method of dividing butter and the like into uniform portions, consisting in forming the material into a continuous freely supported stream of uniform cross-section, cutting off uniform portions from said stream, pressing said portions from two opposite directions into uniform shape, and rejecting in such pressing all material in excess of a given quantity.

2. A device for dividing a stream of plastic material into uniform portions, comprising a plurality of open-ended moulds of a cross-section substantially equal to that of the stream, a horizontal guideway supporting the stream freely in position to enter the moulds a plunger adapted to enter the moulds in opposition to the stream, a cutter for severing the stream close to the moulds, a pair of opposing press plungers, means for supporting the moulds between said plungers for a compression of their contents, means for discharging from the moulds any material not containable between the opposing plungers, an expelling plunger, and means for

supporting the moulds in position to receive said expelling plunger.

3. A device for dividing a stream of plastic material into uniform portions, comprising a plurality of open-ended moulds of a cross-section substantially equal to that of the stream, a series of rollers supporting the stream in horizontal position, means for supporting said moulds in position to receive the stream, a plunger adapted to enter the moulds in opposition to the stream, a cutter for severing the stream close to the moulds, a pair of press plungers, means for supporting the moulds between said plungers for a compression of their contents, one of said latter plungers having apertures for the discharge of material not containable between the advanced plungers, an expelling plunger, and means for supporting the moulds in position to receive said expelling plunger.

20 4. A device for dividing a stream of plastic material into uniform portions, comprising a plurality of open-ended moulds of a cross-section substantially equal to that of the moulds,

supporting means for said moulds allowing them to be moved through a plurality of operating positions, a horizontal guidway for passing the stream into the moulds in one of said operating positions, a plunger held in position to enter the moulds in opposition to the stream, a cutter for severing the stream close to the moulds, a pair of opposing press plungers arranged in another operating position for insertion from opposite sides into the moulds, one of said latter plungers having apertures for the discharge of material not containable between the advanced plungers, an expelling plunger arranged in a third operating position and adapted to pass through the moulds for the discharge therefrom of the pressed portions of material, and means for receiving said portions from the moulds.

5. A structure as claimed in claim 4 wherein the mould supporting means consists of a rotary carrier wherein the moulds are held equidistant from the axis of rotation.
